UNITED STATES PATENT OFFICE.

WILLIAM G. WEST AND RODERIC S. FOSTER, OF AURORA, ILLINOIS.

DESIGN FOR A LAMP BASE AND STANDARD.

50,857.

Specification for Design.

Patented May 29, 1917.

Application filed February 21, 1917. Serial No. 150,282. Term of patent 7 years.

To all whom it may concern:

Be it known that we, WILLIAM G. WEST and RODERIC S. FOSTER, citizens of the United States, residing at Aurora, in the county of Kane and State of Illinois, have invented a new and original and ornamental Design for a Lamp Base and Standard, of which the following is a specification, reference being had to the accompanying drawing, forming part thereof.

The figure is a perspective view of a lamp base and standard.

We claim:

The ornamental design for a lamp base and standard, as shown.

WILLIAM G. WEST.
RODERIC S. FOSTER.

Witnesses:

C. H. BORNGREBE,
A. N. HEALY.
